CLAIM

The ornamental design for a dosing cap tip, as shown and described.

DESCRIPTION

FIG. 1 is an elevated perspective view of the dosing cap tip mounted to a dropper within a vial;

FIG. 2 is an elevated perspective view of the dosing cap tip depicted in FIG. 1;

FIG. 3 is an inverted perspective view of the dosing cap tip depicted in FIG. 1;

FIG. 4 is a front view of the dosing cap tip depicted in FIG. 1 where the right side, left side, and rear views are identical to FIG. 4;

FIG. 5 is a top view of the dosing cap tip depicted in FIG. 1; and

FIG. 6 is a bottom view of the dosing cap tip depicted in FIG. 1

The broken lines in the figures depict a vial and dropper engaging the dosing cap tip, the vial and dropper forming no part of the claimed design.
